UNITED STATES PATENT OFFICE.

LUCIEN A. DEXTER, OF GRAND RAPIDS, MICHIGAN.

LATCH.

Application filed July 8, 1925. Serial No. 42,280.

To all whom it may concern:

Be it known that I, LUCIEN A. DEXTER, a citizen of the United States of America, residing at Grand Rapids, in the county of Kent and State of Michigan, have invented certain new and useful Improvements in Latches; and I do hereby declare the following to be a full, clear, and exact description of the invention, such as will enable others skilled in the art to which it appertains to make and use the same.

This invention relates to latches adapted for ready application to doors, the present latch being adapted when made in different sizes for application to screen doors, cupboards or kitchen cabinets and to larger doors, such as the doors of houses and the like. It is a primary object and purpose of the present invention to construct a latch which can be very easily installed, requiring merely the boring of a cylindrical hole in the edge of the door and a transverse cylindrical opening through the door so as to cut across the opening bored in the edge of said door. A further object of the invention is to provide a latch which is of simple structure, very easily formed and assembled and which in service is particularly durable and efficient.

To these ends and to others which will later appear as understanding is had of the invention I have constructed the latch described in the following description and illustrated in the accompanying drawing, in which,

Fig. 1 is a horizontal section at the edge of the door showing the latch installed therein, portions of the latch being shown in horizontal section and others in plan.

Fig. 2 is a vertical section through the door at the place of application of the latch, the latch barrel being shown in longitudinal vertical section.

Fig. 3 is a view similar to Fig. 2, the interior mechanism of the latch shown in side elevation in Fig. 2, being shown in vertical section in Fig. 3, and

Fig. 4 is an enlarged perspective view of the latch bolt.

Like reference characters refer to like parts in the different figures of the drawing.

In the construction of the latch an outside casing or barrel 1 open at one end and completely closed by an end 2 at its inner end is provided, the same being preferably

drawn from a single piece of metal. This casing or barrel is provided with circular openings 3 in opposite sides at a point between its ends.

Within the latch casing or barrel thus made a latch bolt is slidably mounted. In the construction of the bolt a sheet of metal is properly formed and rolled into cylindrical shape, the front end 4 thereof being of cylindrical form from which spaced apart parallel narrow upper and lower sides 5 extend to the rear and connect with the rear cylindrical section 6 which, at its inner end and at its upper and lower sides, is formed with triangular projections, indicated at 7. Within the cylindrical rear portion 6 a plug 8 is located, its front end being formed into a wedge 9 lying between the triangular projections 7 previously described. The plug is formed with an integral rear extension 10 of smaller diameter than the plug 8. The plug 8 is permanently secured within the cylindrical portion 6 by indentations 11 made in the opposed sides of said part 6 and pressed into suitable openings made in the sides of the plug as shown in Fig. 3.

At the front end of the latch bolt a strike 12 of cylindrical form having the same diameter as the part 4 is located, its outer end being beveled to make an inclined cam strike surface 13. The strike 12 is reduced in diameter so as to make an inwardly extending portion 14 passing into the front end of the cylinder 4 to which it is permanently secured by indenting the cylinder 4 at opposed points, at 15, into suitable recesses in the part 14 similar in all respects to the method by which the plug 8 is secured in place. The latch bolt thus made is designed to be inserted in the open outer end of the casing 1, a coiled spring 16 being located at the inner end of the casing and against the closed end 2 thereof at one end, its opposite end bearing against the plug 8 and being located around the smaller projection 10 extending therefrom.

The housing 1 with the bolt and spring therein is designed to be inserted in a cylindrical opening bored in the edge of the door D. The operating member for the bolt comprises a bar 17 substantially square in cross section at each end to which knobs 18 are detachably secured, there being the usual escutcheons 19 disposed between the sides of the door and the ends of the knobs. Prior

to the insertion of the latch housing with the bolt and spring therein a second opening 20 circular in form is bored transversely through the door cutting across the opening in which the housing 1 is to be placed. Then by pressing inwardly on the end of the latch bolt to compress the spring the operating member 17 may be passed through the openings 3 in the housing and through the openings in the latch bolt made between the cylindrical portions 4 and 6 thereof. The intermediate portion of the operating member between its substantially square ends 17 is formed into trough shape, as indicated at 21, the outer side being semi-circular and the inner side substantially V-shape as shown to correspond with the form of the wedge 9 which normally seats against the inner side of the trough under pressure of the spring 16. It is, of course, apparent that one of the knobs 18 is removed from the operating member 17, while this assembly is taking place, being attached after the assembly is complete.

In the operation of the latch the spring 16 normally forces the same outward to the position shown in Figs. 1 and 2, the wedge 9 of the plug 8 and the triangular projections 7 of the latch bolt seating against the inner V-shaped side of the operating member. When the door is closed the cam side 13 at the end of the latch bolt riding against a suitable strike plate acts to force the bolt inwardly against the spring 16 until the opening in the strike plate, common with latches, is reached whereupon the spring forces the bolt outwardly into engaging position with the strike plate. To open the door it is necessary merely to grasp one of the knobs 18 and turn the same in either direction. This causes a retraction of the bolt to the position shown in Fig. 3, or until the end of the part 10 comes against the closed end 2 of the latch housing, spring 16 being compressed so that it is located wholly around the part 10. When this extreme inward movement has been reached by the latch bolt the wedge 9 of the plug 8 at its end and the ends of the triangular projections 7 extend a short distance inward from the rear side of the circular openings 3 in the housing 1, thereby making a positive stop against any further turning movement of the operating member. The wedge, being solid entirely across the bolt, is very durable and irrespective of how much force may be applied to the operating member 17 there is no danger of cutting off the projecting end of the wedge so as to destroy its effectiveness as a stop. This is particularly desirable inasmuch as the operating member 17 for practical purposes must be made of iron and if the same comes against a weak stop member of soft material, such as brass, there is present a liability that

the stop member will eventually be destroyed by the operating member when the same is forcefully actuated.

The construction described is very simple, exceptionally easy of installation and is in many respects a great improvement over prior door latches. The construction of the latch bolt is simple and the same can be very readily formed and assembled in quantity production at very low cost. The invention is defined in the appended claims and is to be considered as comprehensive of all forms of structure coming within their scope.

I claim:

1. A latch comprising, a tubular housing having a closed end, a latch bolt slidably mounted in the housing provided with an opening therethrough, said bolt at the inner end of said opening being formed with a forwardly projecting portion, and at its inner end having a reduced extension projecting toward the closed end of the housing, a spring disposed between the closed end of the housing and the end of the latch bolt around said extension, and an operating member passing transversely through the housing and latch bolt formed with means to engage said forwardly projecting portion of the latch bolt and thereby move the bolt inwardly until said extension engages against the closed end of the housing.

2. A latch comprising, a tubular housing having a closed inner end, a latch bolt slidably mounted in the housing, said latch bolt being formed with an intermediate tubular section having openings cut therethrough in opposite sides, a strike member secured in the outer end of said tubular section, and a plug secured in the inner end of said tubular section, said plug at its front end being formed into wedge shape and at its rear end with a reduced extension projecting beyond the end of said tubular section, a spring located between the end of the latch bolt and the closed end of the housing around said extension, and an operating member extending transversely through the housing and the openings in the latch bolt, said operating member being formed with a portion against which the wedge portion of the plug engages and shaped in substantial conformity with said wedge portion, substantially as described.

3. A latch comprising a tubular housing having a closed end and formed with circular openings in opposite sides thereof between its ends, a latch bolt having an elongated opening therethrough slidably mounted in the housing, spring means normally forcing the latch bolt outward, an operating member extending through the openings in said housing and latch bolt, said operating member and latch bolt having interengaging means whereby the bolt is moved in-

- wardly on rotation of the operating member in either direction, and means on the latch bolt adapted to engage with the closed end of the housing when moved inwardly a predetermined distance, whereby said interengaging means on the latch bolt engaging with the operating member serves as a stop to prevent further rotation of the operating member, substantially as described.
4. In a latch, a tubular housing open at one end and having a closed inner end, said housing having openings in opposite sides, a latch bolt formed with an elongated opening therethrough and at the inner end of said opening having a wedge-shaped portion extending into said opening, said latch bolt being also formed with a reduced extension at its inner end extending toward the closed end of the housing, a spring between the end of the latch bolt and closed end of the housing, an operating member extending transversely through the opening in the housing and latch bolt and formed with means to engage said wedge portion whereby on rotation of the latch member in either direction the latch bolt will be retracted until the end of the said extension engages against the closed end of the housing, said wedge portion projecting partly into the plane of the openings through the housing and serving as a stop against further rotation of the operating member.
5. A latch bolt of the character described comprising, a tubular section having portions cut away to make openings at its upper and lower sides and having triangular-shaped projections extending forward into said openings, a cylindrical strike member having a beveled outer end fixed in one end of the tubular member, a plug fixed in the other end of the tubular member and formed at one end with a wedge portion lying between said triangular projections and at its opposite end with a cylindrical extension of reduced diameter which extends beyond the end of said tubular member, substantially as described.

In testimony whereof I affix my signature.

LUCIEN A. DEXTER.
